UNITED STATES PATENT OFFICE

2,469,258

SHARPENER

Jacob Brockley, Newport News, Va.

Application January 23, 1947, Serial No. 723,837

1 Claim. (Cl. 51—214)

1.

This invention relates to sharpeners, and more particularly to a combined knife, scissors and razor blade sharpener.

It is an object of this invention to provide an improved sharpener of the kind to be more specifically described hereinafter which is convenient and inexpensive, simple in construction and operation, to facilitate the sharpening of knives, scissors and razor blades to fill a need of such a device in homes and many business establishments.

Another object of this invention is to provide a tool of this kind having an abrasive wheel for sharpening scissors and razor blades and rollers for sharpening knives. A supporting plate is provided in which the scissors may be firmly held while being sharpened so that the proper cutting angle will be provided.

A further object of this invention is to provide a sharpening tool of this kind having an abrasive wheel and sharpening rollers supported on a clamp which may be readily set up on the edge of a table or bench when desired and just as readily removed when the tool is not being used. The abrasive wheel and rollers are rotatably mounted on the clamp in such a manner that they are held against rotation during the sharpening operations but may be rotated by the user when desired to provide for the equal wear on the abrasive surfaces and edges.

With the above and other objects in view, my invention consists in the arrangement, combination and details of construction disclosed in the drawings and specification, and then more particularly pointed out in the appended claim.

In the drawing,

Figure 1 is a side elevation of a tool sharpener constructed according to an embodiment of this invention.

Figure 2 is a front elevation thereof,

Figure 3 is a rear elevation,

Figure 4 is a top plan view partly broken away.

Referring to the drawing, the numeral 10 designates generally a sharpener for scissors, razor blades and knives, which is readily portable and may be attached to the top of a table or bench 11 when in use, and which may be readily stored when desired.

The sharpener 10 comprises a combination of an abrasive wheel 12 for sharpening scissors and razor blades, and a pair of rollers 14 for sharpening knives or similar cutting instruments. The sharpener 10 comprises a base 15 formed of a flat strip of metal which is adapted to overlie the top surface of a table 11, forming an upper clamping jaw for the device. An L-shaped

2.

clamping member 16 is fixed to the base 15, extending downwardly therefrom, the lower horizontal arm 17 of the clamping member 16 being provided with a threaded bore 18 through which the screw 19 engages for clamping the sharpener 10 to the table.

The base 15 is formed with a vertically extending flange 20 on one side thereof for supporting the abrasive wheel 12. The wheel 12 is provided for sharpening the scissors or razor blades and is preferably made of abrasive material such as silicon-carbide or aluminum oxide for sharpening scissors and oil stone for sharpening razor blades. A headed bolt 21 engages through the upper end of the flange 20 and through the wheel 12 for rotatably supporting the wheel thereon. The bolt 21 is reduced at its inner threaded end as at 22 inwardly of the wheel 12. The head 24 of the bolt is adapted to engage the outer side of the flange 20 and a resilient spider 25 engages about the reduced end 22 of the bolt for frictionally holding the wheel 12 against rotation.

The spider 25 is formed of a washer 26 which is adapted to abut the shoulder 27 formed by the reduced end 22 extending from the bolt 21 and having inwardly extending fingers 28 which press against the side of the wheel 12. The nut 29 may be securely tightened down on the spider 25 which will lock the spider to the wheel and to the screw 21 while permitting the wheel to be rotated by the user and holding it against rotation while the wheel is being used to sharpen a tool.

For supporting the blade of a scissors to be sharpened on the wheel 12, there is provided a Z-shaped supporting member 30 having a lower flange 31 which is adapted to be fixed to the base 15 by rivets 32 or other suitable fastening devices and an upper flange 34 which serves as a platform on which the scissors blade 35 may be rested while the edge is being sharpened. The platform 34 or upper flange of the support 30 is disposed above the base 15 and below a plane parallel to the base through the axis of the wheel 12. The Z-shaped supporting member may be made or formed integrally with the base 15, so a separate part will not be necessary.

The tool supporting member 30 is located approximately 60° from the horizontal plane through the axis of the wheel to provide for the proper cutting edge on the blade 35. A vertically extending flange 36 is formed on the base 15 on a side thereof, at right angles to the flange 20. The clamping member 16 is provided with ears 37 which are adapted to be fastened to the

flange 36 by rivets 38 or other suitable fastening devices. The flange 36 is further formed with a pair of transverse spaced apart upwardly extending arms 39 on which the rollers 14 are rotatably supported.

The rollers 14 are provided for sharpening the edge of a knife 40 and engage each other along the periphery thereof at a point substantially in the plane of the axis of the rollers. The rollers 14 are rotatably mounted on the bolt 41, extending through the finger 39 and the axis of the rollers 14, having a spider 42 on the inner reduced end of the bolt 41. The bolts 41 are constructed in the same manner as the bolt 21 described above, and the spiders 42 are similar to the spider 25 described above, so that the description of the spider 25 and bolt 21 will apply to the spider 42 and bolt 41.

The discs 14 are made of tool steel, hardened and ground on the circumference to provide a suitable cutting medium for sharpening the knives. For sharpening scissors, the abrasive wheel 12 is used. The flat side of the scissors blade is rested on the support 30 in front of the wheel. The cutting edge of the scissors is held against the face of the wheel with a light pressure and the blade is moved from end to end against the wheel until a smooth, sharp cutting edge is developed.

Razor blades are sharpened on top of the wheel and a support is not necessary.

For sharpening knives, the steel rollers are used, the cutting edges of the knives are placed in cutting contact with the cutting edge formed by the rollers 14. With a light pressure the knife is moved from end to end over the rollers until a suitable cutting edge is formed. The spiders 25 and 42 hold the wheel 12 and rollers 14 against rotation while the blade of a tool is being sharpened and may be rotated by the user to permit an even wear on the surface of the

wheel and rollers when the tools are removed from the sharpener.

I do not mean to confine myself to the exact details of construction herein disclosed, but claim all variations falling within the purview of the appended claim.

What I claim is:

A sharpening device comprising a base, an L-shaped clamping member on said base extending downwardly therefrom for clamping said base on a support, a vertically extending flange on said base, upwardly extending arms on said flange, a pair of peripherally engaging sharpening rollers on said arms, headed bolts engaging through said arms and said rollers adjustably mounting said rollers on said arms, a reduced diameter threaded end on said bolts defining a shoulder adjacent said end, a spring spider on said threaded end engaging said rollers and said shoulder for frictionally holding said rollers against rotation, and a nut on said bolts for adjusting the tension of said spider.

JACOB BROCKLEY.
